Primary Examiner — Brian N Vinson(74) *Attorney, Agent, or Firm* — Leanne Taveggia Farrell; Westman, Champlin & Kelly, P.A.(57) **CLAIM**

The ornamental design for a luminaire, as shown and described.

DESCRIPTION

FIG. 1 is a top perspective view of a luminaire showing our new design.

FIG. 2 is side elevational view thereof;

FIG. 3 is a vertical cross-sectional view thereof, taken in the direction of line 3-3 of FIG. 1;

FIG. 4 is a top plan view thereof; and,

FIG. 5 is a bottom plan view thereof.

The broken lines disclosure in the views is understood to represent a portion of the article in which the claimed design is embodied, but which forms no part of the claimed design.
